ATTORNEYS.

UNITED STATES PATENT OFFICE.

MICHAEL LALLY, OF NORTH LAWRENCE, OHIO.

MINING-MACHINE.

SPECIFICATION forming part of Letters Patent No. 269,214, dated December 19, 1882.

Application filed April 29, 1882. (No model.)

To all whom it may concern:

Be it known that I, MICHAEL LALLY, of North Lawrence, in the county of Stark and State of Ohio, have invented certain new and 5 useful Improvements in Drilling-Machines; and I do hereby declare that the following is a full, clear, and exact description of the invention, which will enable others skilled in the art to which it appertains to make and use the same, 10 reference being had to the accompanying drawings, which form a part of this specification.

This invention relates to machines for drilling or boring coal, rock, slate, clay, &c.; and it has for its object to lessen the labor in drilling, and at the same time provide a simple, 15 durable, comparatively inexpensive, and efficient machine. To this end it consists in certain improvements in the construction and operation of the same.

20 In the drawings, Figure 1 is a perspective view; Fig. 2, a side view; Fig. 3, a vertical transverse section of the extensible frame; Fig. 4, a detailed perspective view of the drill and its box or bearing detached; and Fig. 5, a cross- 25 section of the latter.

Referring by letter to the drawings, A designates the extensible frame or support of my improved drilling-machine, consisting of two parts, B C, the former, B, having a top 30 casting or cross-piece, D, in the ends of which are fitted the downwardly-extending vertical side pieces, E E, which have collars F, secured at their lower ends, embracing and sliding on the outer perpendicular side pieces, G G, se- 35 cured at their lower ends to a casting or cross-piece, H. The sides G G are connected at their top ends by a band or collar, I, and are provided with perforations J, through which passes a transverse adjusting pin or bolt, K, 40 inserted also through a pair of the transverse perforations L of a series in each side piece, E E. Thus by raising or lowering the inner part, B, and adjusting the pin K the frame may be extended or contracted at will.

45 The top and bottom pieces, C H, of frame A are provided with screws M M for securing and holding the frame in position; and the sides E E and G G are each provided in their edges with a series of transverse semicircular 50 or curved recesses, N, for purposes that will be presently described.

O designates the drill-bearing box, consisting of two plates, P Q, each having a semi-circular screw-threaded groove, R. These plates are fitted together by means of one or 55 more lugs, S S, on the plate P, which enter openings or apertures T T in the plate Q, and by one or more uprights, U U, on the former plate, provided with openings U', in which a wedge or securing-key, V', may be inserted, 60 as shown. The screw-threaded portion V of the drill W works in the opening R of the box O. It is turned or operated by a crank, X, provided with a longitudinal slot, Y, by which it is inserted over the end of the bar 65 V, and adjusted on the same to lengthen or shorten the crank movement. The crank is secured firmly against a shoulder, Z, on the bar V by a thumb-screw, A'.

To the under side of box O is secured a 70 transverse bar or shaft, B', the ends of which, when the box is secured in position between the inner sides, E E, of the extensible frame, are adjusted in the recesses or bearings N in the edge of the sides of the frame. By this 75 means the position of the box may be elevated or lowered, as desired, and by turning it on the shaft B' in its bearings N the drill may be directed to any desired angle, as shown in dotted lines, Fig. 2, of the drawings. 80

The herein-described construction of the extensible frame is of superior utility and convenience, and its adjustment can be quickly and easily effected.

The operation and advantages of my in- 85 vention are obvious. The drill-box possesses many advantages over hinged boxes of like character, and when it becomes worn or loose the plates may readily be separated and filed down to reduce the size of the drill-openings. 90 It will then hold the drill as tight as before, thus obviating the trouble and expense of procuring a new box.

I claim and desire to secure by Letters Patent—

1. The herein-described extensible frame, comprising the parts B C, having end cross-pieces, D H, respectively, to which are secured transversely-perforated side pieces, E E and G G, having semicircular or curved re- 100 cesses N in their edges, the sides E E of the smaller part fitting between the sides of the

larger part C, and provided with collars F, sliding on the sides G G, the latter being provided with a connecting band or collar, I, at their upper end, and the transverse adjusting pin or bolt K, in combination with the drilling mechanism comprising the boxing adjustable in said frame and carrying the drill, as set forth.

2. The herein-described drill-box, comprising the plates P Q, the former being provided with one or more lugs, S S, adapted to enter openings or apertures T T in the latter, and with one or more uprights, U U, provided with openings in which a wedge or securing-key, V', may be inserted to hold the plates together, in combination with the extensible frame and carrying the drill, as set forth.

3. The herein-described improved drilling-machine, consisting of the extensible frame A,

the parts B C of which have the end cross-pieces, D H, provided with the transversely-perforated sides E E and G G, having respectively collars F and band or collar I, and adjusting pin or bolt K, the drill-box O, comprising the plates P Q, having respectively lugs S S and uprights U U, provided with openings U' for the reception of a wedge or securing-key, V', and openings or apertures T T, and the screw-threaded drill W, having the adjustable crank X and set-screw A', substantially as herein shown and specified.

In testimony that I claim the foregoing as my own I have hereto affixed my signature in presence of two witnesses.

MICHAEL LALLY.
